UNITED STATES PATENT OFFICE.

HOWARD GREER, OF CHICAGO, ILLINOIS.

MANUFACTURE OF SPIKES AND MACHINE THEREFOR.

SPECIFICATION forming part of Letters Patent No. 308,251, dated November 18, 1884.

Application filed December 3, 1883. (No model.)

To all whom it may concern:

Be it known that I, HOWARD GREER, a citizen of the United States, residing at Chicago, county of Cook, State of Illinois, have invented or discovered a new and useful Improvement in Manufacture of Railroad-Spikes and Machinery therefor; and I do hereby declare the following to be a full, clear, concise, and exact description thereof, reference being had to the accompanying drawings, making a part of this specification, in which—like letters indicating like parts—

Figure 1 is a front elevation of a machine provided with my improved dies, said dies being shown separated for feeding in a blank. Fig. 2 is a front elevation of the dies in a closed position. Fig. 3 is a similar view of dies for cutting two spikes from a double blank. Figs. 4 and 5 are perspective views of the working-faces of the dies for cutting a single spike. Figs. 6 and 7 are perspective views of the working-faces of the dies for cutting the double blank. Fig. 8 is a perspective view of the single blank. Fig. 9 is a similar view of the double blank. Fig. 10 is a perspective view of the completed spike.

My invention relates to certain improvements in the manufacture of spikes, such as are employed in securing the rails of railway-tracks, in which I propose to use, by preference, Bessemer or open-hearth steel or steel rails or crop ends thereof, though iron may be employed, if so desired; but the granular structure of steel enables it to be employed more advantageously, since, in the absence of fiber, the direction of the line of cut is immaterial, and hence I will describe my invention with particular reference to the use of steel therein. From such material I first produce, by the ordinary or any suitable mode of working, the blank or bar, of any desired length, and having the shape substantially as represented in the drawings, wherein A represents the blank, which is made with a central part, b, of the thickness or approximately the thickness, equal to one side of the spike-shank, and a represents a rib of approximately the size and shape in cross-section which it is desired to give to the overlapping spike-head, and c represents a rib rolled on the opposite side of the same edge of the blank, for purposes presently to be stated. The opposite edge of the blank or bar is made with bevels e e, of sub-

stantially the form and taper which it is desired to give to the spike-point. The blank or bar thus formed I propose to cut by transverse cuts parallel with each other into spike-blanks, and that part of the rib c appertaining to each blank so cut I swage or compress in such manner that it shall expand onto and fill out the lateral sides of the spike-head, so as to make on each side of the head the projecting ears s, such as are required in order that the head may be conveniently caught by the usual claw-bar for the purpose of drawing the spike, when desired. These lines of cut are represented by the dotted lines n n in Figs. 8 and 9. To do this work of shearing the blank and swaging up the ears s, I employ a pair of dies, B B', suitably shaped for this work, and mount them in any suitable machine, one such being represented in the drawings, where D represents the housings and D' represents the plunger or piston or die-carrier, adapted to be moved up and down by an eccentric, d, operated by power suitably applied to the shaft R. On the plunger or die-carrier D', I secure the upper die, B, and make the contrary or lower die, B', stationary on the foundation of the machine, and arrange the dies in such position that the upper or moving die, B, may operate with a shearing cut across the edge of the lower die, B'. The lower face of the upper die, B, is, as represented in the drawings, made to correspond in shape and size with the headed side of the spike-blank, and the lower die is shaped to correspond with the shape of the opposite side of the blank, or with a suitable cavity to receive the rib c. The width of the face of the upper die, B, in the direction of the line of feed, is equal to the width of the spike-blank to be cut off, or equal to one side of the shank b, and at such distance terminates in the vertical wall g, which operates as a stop in effecting proper length of feed between the shearing strokes of the upper die. In this wall I cut a groove, g', at such point and for such depth that a portion of the metal of the rib c, when pressed therein, may flow up or into such groove, and so form one of the ears of the completed spike; and in the adjacent face of the other die, B', I make a like groove or depression, h, of suitable size and depth to form by the pressure of the metal therein the opposite ear, s, of the spike-head. Along the inner wall of the lower die, B', I make a ledge,

r, which projects forward beneath the working-faces of the upper die, *B*, a distance equal to the width of blank cut off, and give to the upper die, *B*, such length of motion or stroke that it will not only cut off the blank at each downward movement, but will also carry the blank so cut off down with it and grip it tightly between the working-faces of the upper die, *B*, on the top surface of the ledge *r*, and for this purpose the ledge *r* and the upper face of the upper die should at a point corresponding with the point of the spike-blank have the proper bevel *r'*. The remainder of the working-face of the ledge *r* should be straight or otherwise conform to the rear face to be given to the spike, except that at the point immediately back of the head-forming portion, where a groove, *r*², is made of a depth such that it may properly form the rearward-projecting lip, *s'*, on the spike-head when such lip is desired.

In the operation of the machine with the operating-die raised to its highest position, the dies will be open for the feed of the bar or blank. This feeding may be done by hand or by suitable machinery in a line at right angles to the length of the dies, and with the rib *c* resting in the groove *f* of the lower die. The end of the blank or bar is fed forward until its end strikes the wall *g*, and the downstroke of the operating-die *B* then shears off the blank, and with its downward motion grips the point and shank thereof tightly on the ledge *r*, and at the same time the rib *c*, coming into the groove *r*², meets with such resistance that the larger portion of the ribs *c* is pressed laterally out into the grooves *g'* and *h*, so as thereby to form the ears *s* on the sides of the spike-head, and the remainder of the metal remaining in the groove *r*² forms the lip *s'* of the spike-head.

It will be understood of course that the blank is to be properly heated before being fed into the machine, so that this compress or swaging action on the rib *c* may thereby be facilitated.

The upper or feeding face, *l*, of the lower die is constructed to conform with the lower side of the blank, so as to properly guide said blank when being fed between the dies. In Figs. 3, 6, and 7, I have shown the same construction of dies provided with grooves, except that they are duplicated so as to cut two spike-blanks point to point, and finish them at the same operation, the spikes being severed by the projections *o*, formed by the meeting of the bevels *r'*.

In so far as relates to the form or forms of blank herein shown and described, the same is not claimed herein, as it will form the subject-matter of another application, to be filed in due time.

In an application, No. 113,387, filed December 3, 1883, I have described and claimed a machine for forming the lateral ears on a spike-head by means of a heading-die moving in a plane parallel with the length of the

spike; but in the machine described and claimed herein the lateral ears are formed by the compressive action of a die moving at right angles to the body of the spike.

I herein claim as my invention—

1. The die *B*, having a feeding-face, *l*, conformed by a groove and bevel to the shape of the blank to be operated on and a ledge beneath the same, and on the shearing side thereof grooved, as at *r*², and also beveled and having also a groove, *h*, in the adjacent wall, in combination with a reciprocating shearing-die, *B*, having a compressing - face, also grooved and beveled, and having also a groove, *g'*, in the vertical wall thereof, substantially as described.

2. The die *B*, provided with the vertical wall *g*, having therein the groove *g'*, opposite the head of the blank on one side thereof, in combination with the die *B'*, provided with the groove *h*, opposite the head portion of the blank and on the other side thereof, substantially as set forth.

3. The die *B*, provided with the vertical wall *g*, having therein the groove *g'*, opposite the head of the blank on one side thereof, in combination with the die *B'*, having the ledge *r*, and the groove *h*, opposite the head portion of the blank and on the other side thereof, and having also the groove *r*², located at the back of the head, substantially as set forth.

4. The herein-described method of manufacturing spikes, which consists in rolling or forging a blank of approximately the size and shape in cross-section of the finished spike, cutting said blank into spike-blanks by a series of parallel cuts in suitable dies, and then finally forming said spike by compression between suitable-formed faces on the same dies, and simultaneously and by the same compression forcing laterally outward or expressing a portion of the metal to form side lips on the head, substantially as set forth.

5. In the manufacture of spikes from transversely-cut blanks, the method of forming the side ears, *s*, on the spike-head by swaging a portion of the metal *c*, provided for the purpose on the back of the head, laterally into suitable grooves provided for the purpose, substantially as set forth.

6. In the manufacture of spikes from transversely - cut blanks, the method of forming the side ears, *s*, on the spike-head, and the lip *s'* on the back thereof, by swaging a portion of the metal *c*, provided for the purpose on the back of the head, laterally into side grooves provided for the purpose, the residue of such metal forming the lip, substantially as set forth.

In testimony whereof I have hereunto set my hand.

HOWARD GREER.
